WELL PERFORATING APPARATUS

Blake M. Caldwell, Fort Worth, Tex., assignor to Jet Research Center, Inc., Arlington, Tex., a corporation of Texas

Filed Apr. 3, 1957, Ser. No. 650,334

3 Claims. (Cl. 102—20)

This invention relates to well perforating apparatus and more particularly to such apparatus in which individual shaped explosive charge units are linked together to form a chain of units. The invention also relates to the individual shaped charge explosive units themselves.

In the perforation of oil wells, it is desirable to have perforating apparatus that may be quickly assembled in the field to provide a perforating gun of a length and having a number of perforating units suited to the job at hand. For the sake of simplicity and speed of operation, it is also desirable that a minimum number of tools be needed to assemble the perforating apparatus.

Frequently, oil wells are completed by so-called permanent type completion methods. In these methods, tubing is set in the casing and the top of the casing is capped with the usual well head equipment prior to performance of the perforating step. Perforating apparatus is then lowered by cable through the tubing and out of its lower end to the level at which the casing is to be perforated and the apparatus is fired. Any parts of the perforating apparatus that remain attached to the cable after firing are retrieved by withdrawal through the tubing. For these purposes, the perforating apparatus must be as efficient as possible. One requirement is that the apparatus must have a close sliding fit in the tubing in order to accommodate the largest possible quantity of explosive in each perforating unit which is designed to fire generally laterally of the well bore. At the same time, the apparatus must not bind in the tubing during descent.

The permanent type completion method is being adapted to directional wells wherein the well may be drilled vertically for a certain distance down from the earth's surface, and thereafter drilled at an angle to the vertical. Also, in some offshore installations the production tubing may rise vertically from the bottom of the well and thereafter be turned landward and run to the shore. In either case, the tubing is rather sharply bent at certain points which makes it very difficult to run perforating apparatus through the tubing.

An object of the invention is to provide a well perforating apparatus which may be quickly assembled in the field principally from a plurality of identical, shaped explosive charge units. Due to the special construction of the charge units, such assembly may be accomplished without the use of tools.

Another object is to provide a perforating unit, a plurality of which may be linked together to form a perforating assembly of any desired length.

Another object of the invention is to provide a perforating assembly having articulated joints and being adapted to pass through relatively sharp bends in small diameter tubing. In addition to being adapted to pass through relatively sharp bends that are purposely made in tubing, it is a further object of the invention to provide a perforating assembly that can be run through closely fitting tubing that is inadvertently bent, twisted, dented or otherwise damaged to a limited degree, as by being burried or somewhat corroded in the bore.

2

Still another object is to provide apparatus for perforating oil, gas and water wells that may be employed in permanent type completion methods.

Yet another object of the invention is to provide well perforating apparatus that is relatively simple and inexpensive to manufacture and that may be conveniently and rapidly assembled in the field.

These and other objects and advantages of the invention as may appear hereinafter are achieved in a well

10 perforating apparatus that is adapted to be passed through small diameter tubing having relatively sharp bends which includes a plurality of longitudinally aligned well perforating units and means linking the units together to form a chain having a plurality of spaced articulated joints. The articulated joints lend flexibility to the chain of units permitting it to pass through sharply curved sections of narrow tubing. The articulated joints may include a pivot pin carried by one unit received in a complementary hole provided in an adjacent unit. Such joints include means for maintaining the joint elements in an interlocked condition when the units are in alignment while permitting substantial pivotal movement of adjacent units without unlocking of the joint elements. However, when adjacent units are rotated relative to each other through a wide predetermined angle, the locking means is adapted for quick release whereby the units may be quickly separated. In similar manner, the units may be easily and quickly assembled to form a chain.

20 The perforating units of the invention are so constructed that the shaped charge container has an upstanding arm and a depending arm carrying complementary linking elements. The arms are disposed at a substantial angle to each other about the vertical axis of the unit so that when linked together adjacent units are disposed at an angle to each other about the vertical axis of the assembly, whereby the perforation pattern produced thereby is distributed circumferentially as well as vertically along the well casing.

25 Described in somewhat greater detail, the shaped explosive charge well perforating apparatus of the invention includes a plurality of vertically aligned well perforating units, each unit including a pressure resistant, frangible container having a shaped explosive charge therein adapted upon detonation to project an explosive jet outwardly through the front wall of the container and having a vertical axis intersecting the axis of the explosive jet at a substantial angle, the vertical axes of the units being in alignment along the vertical axis of the well perforating apparatus. The container of each unit has an upstanding and a depending arm. Means is provided for linking the depending arm of each container to the upstanding arm of the immediately subjacent container for pivotal movement about a point on the vertical axis of the well perforating apparatus.

30 More particularly, one of the arms of the container has a terminal planar face containing the vertical axis of the well perforating apparatus and a cylindrical pin is carried by this arm. The pin extends from the terminal face and has its axis intersecting the vertical axis at right angles. 35 A key is carried by the pin and extends radially from the pin at right angles to the vertical axis and is spaced from the terminal face. The other of the arms also has a terminal planar face through which the vertical axis passes and the planes of the terminal faces of the two arms are rotated at a substantial angle to each other about the vertical axis. The other arm has a cylindrical hole therethrough having its axis intersecting the vertical axis at right angles. The other arm provides a keyway therethrough communicating with the hole and extending radially from the hole along the vertical axis. The transverse sectional outline of the hole and keyway conforms in shape to, and is slightly larger than, the transverse sec-

tion outline of the pin and key. The radius of the key is greater than the radius of the hole and the thickness of the arm axially of the hole and adjacent thereto is slightly less than the spacing between the key and the terminal face of the arm that carries the pin.

The perforating units are linked together to form a chain wherein the pin of one unit is received in the hole of an adjacent unit, the terminal faces of the arms are in abutment, and the key overlies the arm of the adjacent unit opposite its terminal face and is out of registry with the keyway.

The invention will be described with greater particularity with the reference to the drawing in which:

Fig. 1 is a vertical sectional view through an oil well showing an exemplary embodiment of the well perforating apparatus of the invention suspended in the well;

Fig. 2 is an enlarged elevational view of one of the shaped charge perforating units used in the apparatus of Fig. 1, parts of the shaped charge container being broken away;

Fig. 3 is a left hand view of the perforating unit shown in Fig. 2;

Fig. 4 is a plan view of the unit shown in Fig. 2;

Fig. 5 is a bottom view thereof;

Fig. 6 is a still further enlarged fragmentary view showing one of the articulated joints of the well perforating apparatus; and

Fig. 7 is a right hand view of the joint shown in Fig. 6.

Referring to the drawing, particularly to Fig. 1, there is shown a section of an oil well having a casing 10 in which production tubing 11 is set. The perforating apparatus of the invention is shown as being suspended from the cable 12 which carries, as is conventional, a conductive wire through which current is passed for the purpose of firing the well perforating apparatus. The well perforating apparatus is lowered from the surface of the earth in well known manner.

The cable head 13 hangs from the lower end of the cable. From the bottom of the cable head an arm 14 depends, and this arm supports a plurality of interlinked, shaped explosive charge, well perforating units designated by the general reference numeral 15. The perforating units are fired in a manner to be explained more fully hereinafter by a detonating fuse or Primacord 16 disposed adjacent the ends of the shaped charge units. Affixed to the lower end of the Primacord 16 in detonating relation thereto is a detonator or blasting cap 17. A pair of wires 18, through which igniting current is conducted to the blasting cap 17, extend from the blasting cap and are wound in an upward direction about the chain of 50 perforating units to enter the cable head 13 in which they are connected to the firing circuit.

The perforating apparatus is seen partially inside of the lower end of the tubing 11. Before firing it is lowered below the bottom of the tubing to a point opposite the 55 section of the casing to be perforated.

Referring to Figs. 2 through 5, the perforating unit of the invention has a charge case 19 closed at its rear end by a cap 20. The cap fits tightly in the rear end of the case and the case may be sealed against ingress of bore fluids by means of an O-ring 20a or similar compressible seal interposed between the cap and the case. Disposed within the case near the rear end thereof is a charge of compressed high explosive 21 having a forwardly facing cavity therein lined with an inert liner 22, preferably of copper or other metal. Stand-off space is provided between the front face of the liner 22 and the front wall 23 of the charge case to permit the perforating jet to form within the case upon detonation of the charge.

The cap 20 has a rearwardly projecting cylindrical boss 24 through which is bored a vertically extending fuse passage 25. As shown in Fig. 5, the cap 20 has a booster cavity 26 separated from the fuse passage 25 by a thin wall 27 through which detonating energy from the Primacord is transmitted to a booster charge in the cavity.

The booster charge initiates the main explosive charge 21 to produce an explosive jet from the liner, the jet being projected forwardly along the cylindrical axis of the charge. This jet forms in the air space forwardly of the liner 22 and penetrates the front wall 23 of the charge case. Thereafter it penetrates the wall of the adjacent casing and perforates the surrounding earth formation. Upon detonation, some of the energy of the explosive charge serves to break or fracture the charge case and arms, forming small fragments and particles that fall harmlessly to the bottom of the well.

The charge case has an upstanding arm 27, the face 28 of which contains the vertical center line CL of the unit. The face 28 is disposed at right angles to the charge axis. From the upper terminal end of the face 28 a cylindrical pivot pin 29 extends perpendicularly, the axis of the pin intersecting the center line. A key 30 projects radially from the end of the pin 29 in a direction at right angles to the center line as seen in Fig. 3. As shown, the upstanding arm 27 is of uniform thickness; however, the thickness does not have to be uniform as long as the terminal end of the planar face 28 adjacent the pin 29 is in a plane containing the center line.

The case of the unit also has a depending arm 31 which, in the embodiment shown, is of the same length as the upstanding arm 27. The surface 32 of the depending arm contains the center line of the perforating unit. A cylindrical hole 33 is formed in the lower end of the depending arm. This hole is at right angles to the plane of the surface 32 and its axis intersects the center line. Extending upwardly from the hole 33 is a keyway 34 that communicates with the hole and extends in a vertical direction along the center line of the perforating unit. The keyway extends entirely through the arm 31. In the particular form shown, the terminal end of the depending arm is of uniform thickness and the lower end of the face 32 contains the center line. However, the end of the arm near the case may be thicker or thinner than shown as desired. It will be noted that the depending arm makes an angle of 30° with the axis of the shaped explosive charge as best seen in Fig. 5.

Figs. 6 and 7 show in enlarged fragmentary detail the manner in which the upstanding arm 27 of one perforating unit is linked to the depending arm 31 of an immediately superadjacent shaped charge unit. It will be seen that the pin 29 is received in the hole 33 with the key 30 overlying the rear face 35 of the depending arm. With the charges linked in vertical alignment, the key 30 is 90° out of registry with the keyway 34 and the arms 27 and 31 are interlocked, that is to say the pin cannot be moved axially from the hole 33. However, the pin 29 is free to pivot in the hole 33 through an angle of nearly 90° in a counter-clockwise direction as seen in Fig. 6 without danger of the arms becoming disengaged. The arm 27 may pivot in a clockwise direction as seen in Fig. 6 more than 90° without danger of disengagement. The diameter of the hole 33 is somewhat greater than the diameter of the pin 29 providing a loose fit of the pin in the hole. It is also seen that the radius of the key 30 is somewhat greater than the radius of the hole 33 so that the key will overlie the rear face 35 of the depending arm and maintain the arms engaged. The profile of the key 30 is similar to but smaller than the profile of the keyway 34 making for easy engagement and disengagement of the arms when it is desired to link or unlink charge units. Referring to Fig. 7 it is seen that the distance from the terminal planar face 28 of the arm 27 to the inner face of the key 30 is somewhat greater than the thickness of the depending arm 31, providing for a free fit of the arm 31 between the key and the arm 27. This free fit allows limited rocking movement in the plane of the drawing of the arm 31 in relation to the arm 27 and thus enhances the flexibility of the assembled perforating gun.

Perforating units in accordance with the invention are

readily unlinked or linked without the use of any tools, as will be apparent from a consideration of Fig. 6. To unlink adjacent units, the arm 27 is rotated counterclockwise 90° to swing the key 30 into registry with the keyway 34. The arm 27 may then be disengaged from the arm 31 by simply sliding it to the rear as seen in Fig. 6. Conversely, adjacent units are linked together by aligning the key 30 with the keyway 34 and inserting the pin 29 in the hole 33. Thereafter the arm 27 is rotated 90° in the clockwise direction so that the key overlies the surface 35 of the arm 31. As seen from Fig. 7, the terminal planar face 32 of the arm 31 is opposed to the terminal planar face 28 of the arm 27 when the units are properly assembled. Thus the center lines of adjacent charge units are substantially in alignment.

Although the angular relationship of the key 30 and keyway 34, in the illustrative embodiment shown, requires that adjacent linked charge units be turned 90° from axial alignment to unlock and disengage them, it will be understood that other angular relationships may be employed requiring either a somewhat greater or lesser relative rotation for engagement or disengagement of adjacent units.

The charge units in assembled relationship as shown in Fig. 1 are adapted to be run through narrow tubing with close clearance. For this purpose, the charge containers are especially dimensioned to provide surfaces that will slide through narrow tubing without binding and will maintain alignment of the charge units. As seen in Figs. 2, 4 and 5, the front face 23 of the charge case is a segment of a sphere having its center on the center line of the charge unit at its intersection with the horizontal axis of the charge case 19. The boss 24 has a spherical rear face with its center at the same point and having the same radius as the front face 23. The circular rear edge of the charge case 19 lies in this sphere as does also the circular forward edge of the charge case where the spherical front face 23 intersects the cylindrical portion of the case 19. Thus it is seen that the charge case and cap provide a container in which all surfaces that can slide against the tubing are located on a spherical surface having its center on the center line of the perforating unit and preferably at a point midway between the axis of the pin 29 and the axis of the hole 33. Whereas, the arms 27 and 31 are shown as being of equal length, it will be understood that they may have different lengths, if desired, or they may be proportionately longer or shorter than shown in the drawings.

Owing to the hereinbefore described geometry of the charge unit, a linked assembly of such units will readily pass through a straight length of tubing having a bore with a diameter only slightly larger than the diameter of the spherical surface containing the faces and edges of the charge container that make sliding contact with the bore of the tubing. These faces and edges are termed the skating faces of the charge container, since they slide or skate along the bore of the tubing. Such an assembly of units is free to rotate on its vertical axis within the confines of closely fitting straight tubing without substantial lateral displacement of any of the units from alignment with the vertical axis of the assembly and without becoming lodged in the tubing as it is lowered therethrough. Moreover, the articulated joints linking adjacent units together and the angular phasing of such joints about the vertical axis of the assembly allow the assembly to pass readily through rather sharply curved lengths of closely fitting tubing.

The foregoing is exemplified in an actual embodiment of the invention constructed in accordance with the accompanying drawing in which the distance between centers of the pin 29 and the hole 33 was 3", the diameter of the spherical surface containing the aforementioned faces and edges of the charge container was $1\frac{1}{16}$ ", and the center of the spherical surface was located on the center line of the charge unit midway between the pin 29 and

the hole 33. Ten charge units so constructed and dimensioned when linked together to form a chain, as shown in Fig. 1, were found to run freely in straight lengths of tubing having a bore measuring 2" in inside diameter and to negotiate bends in such tubing having a radius of 5' without binding or becoming lodged therein.

In preparing or assembling a perforating gun in the field, a charge 15 is linked to the arm 14 of the cable head 13. The arm 14 has a hole and keyway therethrough, similar to the hole and keyway of the charge unit hereinbefore described, in which the linking pin of the top-most charge unit is inserted. As many additional perforating units as desired are added to form a chain of units. It will be seen that adjacent charge units are disposed at an angle of 120° to each other about the vertical axis of the assembly. Detonating fuse 16 is threaded through the passageways 25 of the perforating units and wound about the assembly in helical disposition as shown. The lower end of the fuse 16 is equipped with a detonator 17, the wires 18 of which are led upwardly to the cable head in which they are connected to the firing circuit whereby the detonator may be initiated from the surface of the earth. The assembly is lowered into the well as shown in Fig. 1 to the desired level. The firing circuit is energized. The blasting cap 17 detonates the Primacord 16 which practically simultaneously detonates the individual perforating units 15 to perforate the casing and surrounding earth formation. The charge units 15 are frangible and are broken into small fragments which fall to the bottom of the well as innocuous debris. The cable head 13 is of massive construction and is not destroyed by the explosion. It is withdrawn after firing for re-use.

While the well perforating unit shown in the drawings has but a single hole 33 in the depending arm 31, it is contemplated that an additional hole or holes of the same kind may be formed in the arm 31, thus giving a selection of holes in any one of which the pin of an adjacent unit may be inserted, whereby the spacing of the charges may be varied in assembling the units. The plurality of holes are spaced along the center line of the charge unit. Score marks may be made between adjacent holes along which that portion of the arm 31 below the hole that is selected for use may be broken off and discarded.

From the foregoing description of a typical embodiment of the invention, persons skilled in the art will readily perceive a wide variety of variations and modifications coming within the spirit of the invention and the scope of the claims. For example, it is contemplated that the detonating fuse 16 may be fired from the top instead of from the bottom by merely changing the position of the blasting cap 17. It is also contemplated that the lower end of the assembly may be provided with a suitable bullet plug if desired. Moreover, blank interval linking members may be provided between adjacent charge units to increase charge spacing. Such blank interval members are similar to the charge units, insofar as concerns the complementary linking elements, but are simply flat bars of metal carrying no explosive charge. It is also contemplated that the perforating units need not embody shaped explosive charge devices; instead, they may include bullet perforating devices. Although, in the illustrative chain of units herein disclosed, adjacent charges are phased at angles of 120° to each other, any other convenient phase angle may be employed; for example, angles of 60°, 90° or 180° may be found convenient, or all charges may face in the same direction.

I claim:

1. Shaped explosive charge well perforating apparatus adapted to be passed through small diameter tubing having relatively sharp bends comprising: a plurality of vertically aligned well perforating units, each unit including a pressure resistant, frangible container having a shaped explosive charge therein adapted upon detonation to project an explosive jet outwardly through a wall of the container

and having a vertical axis intersecting the axis of the explosive jet at a substantial angle, the vertical axes of said units being in alignment to define the vertical axis of the well perforating apparatus; the container of each unit having a sole upstanding and a sole depending arm; one of said arms having a terminal planar face containing the vertical axis of said unit; a cylindrical pin fixed to said one arm, said pin extending from said terminal face and having its axis intersecting the vertical axis of said unit at right angles; a key carried by said pin, said key extending radially from said pin at right angles to the vertical axis of said unit and being spaced from said terminal face; the other of said arms having a terminal planar face containing the vertical axis of said unit, the planes of said terminal faces being rotated at a substantial angle to each other about the vertical axis of said unit, said other arm providing a cylindrical hole therethrough having its axis intersecting the vertical axis of said unit at right angles and providing a keyway therethrough communicating with said hole and extending radially from said hole along the vertical axis of said unit, the transverse sectional outlines of said hole and keyway conforming in shape to and being slightly larger than the transverse sectional outline of said pin and key, the radius of said key being greater than the radius of said hole, and the thickness of said other arm axially of said hole and adjacent thereto being slightly less than the spacing between said key and the terminal face of said one arm; said perforating units being linked together to form a chain wherein the pin on one of the arms of one of said units is received in the hole in the other of the arms of an adjacent unit, the terminal faces of said arms are in abutment, and said key overlies the arm of said adjacent unit opposite its terminal face and is out of registry with the keyway, each unit being readily detachable from an adjacent unit by rotating the unit about the axis of the pin to align the key with the keyway and withdrawing the pin from the hole.

2. A shaped explosive charge well perforating unit comprising: a pressure resistant, frangible, sealed container having a shaped explosive charge therein adapted upon detonation to project an explosive jet outwardly through a wall of the container, said unit having a vertical axis intersecting the axis of the explosive jet at a substantial angle; a first arm carried by said container and being the sole arm extending thereabove and having a terminal planar face containing the vertical axis of said unit; a cylindrical pin fixed to said arm, said pin extending perpendicularly from said terminal face and having its axis intersecting the vertical axis of said unit; and a key carried by said pin, said key extending radially from said pin at right angles to the vertical axis of said unit and being spaced from said terminal face; a second arm carried by said container and being the sole arm extending therebelow and having a terminal planar face containing the vertical axis of said unit, the planes of said terminal faces being rotated at a substantial angle to each other about the vertical axis of said unit, said second arm providing a cylindrical hole therethrough extending perpendicularly from the terminal face thereof and having its axis intersecting the vertical axis of said unit, said second arm providing a keyway therethrough communicating with said hole and extending radially from said hole along the vertical axis of said unit, the transverse sectional outline of said hole and keyway conforming in shape to and being slightly larger than the transverse sectional outline of said pin and key, the radius of said key being greater than the radius of said hole, and the thickness of said second arm axially of said hole and adjacent thereto being slightly less than the spacing between said key and the terminal face of said first arm, a plurality of such units being interconnectable to form a chain by aligning the pin and key of one unit with the hole and keyway of another unit, inserting the pin into the hole to bring opposite terminal planar faces into abutment, and turning the units about the axis of the pin to align the axes of the units, thus locking the units together.

5 radius of said key being greater than the radius of said hole, and the thickness of said second arm axially of said hole and adjacent thereto being slightly less than the spacing between said key and the terminal face of said first arm, a plurality of such units being interconnectable to form a chain by aligning the pin and key of one unit with the hole and keyway of another unit, inserting the pin into the hole to bring opposite terminal planar faces into abutment, and turning the units about the axis of the pin to align the axes of the units, thus locking the units together.

10 3. A shaped explosive charge well perforating unit comprising: a pressure resistant, frangible, sealed container having a shaped explosive charge therein adapted upon detonation to project an explosive jet outwardly through a wall of the container, said unit having a vertical axis intersecting the axis of the explosive jet at a substantial angle; a first arm carried by said container and being the sole arm extending thereabove and having a terminal planar face containing the vertical axis of said unit; a cylindrical pin fixed to said arm, said pin extending perpendicularly from said terminal face and having its axis intersecting the vertical axis of said unit; and a key carried by said pin, said key extending radially from said pin and being spaced from said terminal face; a second arm carried by said container and being the sole arm extending therebelow and having a terminal planar face containing the vertical axis of said unit, the planes of said terminal faces being rotated at a substantial angle to each other about the vertical axis of said unit, said second arm providing a cylindrical hole therethrough extending perpendicularly from the terminal face thereof and having its axis intersecting the vertical axis of said unit, said second arm providing a keyway therethrough communicating with said hole and extending radially from said hole at an angle to the vertical axis of the unit which differs substantially from the angle which said key makes with the vertical axis, the transverse sectional outline of said hole and keyway conforming in shape to and being slightly larger than the transverse sectional outline of said pin and key, the radius of the said key being greater than the radius of said hole, and the thickness of said second arm axially of said hole and adjacent thereto being slightly less than the spacing between said key and the terminal face of said first arm, a plurality of such units being interconnectable to form a chain by aligning the pin and key of one unit with the hole and keyway of another unit, inserting the pin into the hole to bring opposite terminal planar faces into abutment, and turning the units about the axis of the pin to align the axes of the units, thus locking the units together.
